UNITED STATES PATENT OFFICE

GROVER O. WARDROP, OF MUSKEGON, MICHIGAN, ASSIGNOR TO THE BRUNSWICK-BALKE-COLLENDER COMPANY, OF CHICAGO, ILLINOIS, A CORPORATION OF DELAWARE

MAGNET FOR BOWLING ALLEYS

Application filed April 19, 1929. Serial No. 356,441.

My invention relates to magnets and more particularly to magnets disposed in the beds of bowling alleys to maintain bowling pins, having suitable armatures in the bases thereof, in proper alignment for play. This invention is an improvement in the magnet shown in my co-pending application, Serial No. 262,292 filed March 16, 1928, on an invention in a bowling alley.

10 One object of my invention is to provide a mounting which will support the magnet in a substantially fixed position but which is so constructed that the magnet can move slightly so as to adjust itself to the armature in the 15 bowling pin which engages the poles of the magnet.

Another object is to provide a mounting for the magnet which will permit of the ready removal of the magnet by an operator from 20 above the bed of the alley, and will thus facilitate the replacement of a magnet after it loses strength.

Other objects and advantages will appear as the description proceeds.

25 In the accompanying drawings:

Fig. 1 is a sectional view through a magnet and bowling pin embodying my invention, showing the bowling alley bed broken away; and

30 Fig. 2 is a sectional view on the line 2—2 of Fig. 1.

The alley bed 10 has a hole 11 at each point where a bowling pin 12 is to be located.

Attached to the undersurface of the bed 35 by means of woodscrews 13 is a support or bracket 14. This support may be a metal casting, or formed of other material, and is of a size greater than that of the hole 11. In its central portion it is provided with an opening 15 which is aligned with the hole 11 in the bed.

Depending from the support are oppositely disposed hangers 16 which are provided in their confronting surfaces with aligned substantially vertical grooves 17 terminating short of the lower ends of the hangers.

A U-shaped magnet 20 has aligned apertures 21 in its legs 22 to loosely receive a pin 23. The pin 23 is of a greater length than 50 the width of the magnet, so that when dis-

posed in the apertures 21 its ends will project laterally beyond the legs, to form trunnions which are mounted in the grooves 17.

The hole 11 is closed by means of a pin spot 24 which is provided with elongated apertures 26 in its central portion of a size to loosely receive the ends of the legs 22 of the magnet, and a lug or stop 27 depends from the pin spot between the apertures 26 and has a recess at its lower end which loosely receives the 60 pin 23.

It will be noted that this construction will permit the lateral swinging of the magnet with respect to its support, as well as a vertical sliding of the magnet in grooves 17.

The pin spot and the support are firmly connected together and to the bed by means of screws 28 which reinforce the woodscrews 13 in maintaining the support 14 permanently in place and also serve to align and clamp 70 the parts firmly to the bed.

The bowling pin is provided with a longitudinal bore 29 receiving an elastic tether 30 which tends to elevate the pin as described in my aforementioned application and it has an armature 31 in a recess 32 in its base which is attracted by the magnet and thus maintains the bowling pin in playing position. Particles of dirt and other minor obstructions are at times interposed between the armature and the pin spot and therefore if the magnet were fixed in position it could not exert a maximum force on the armature. But because of the movability of the magnet it is enabled to adjust itself to the surface of the armature 80 and thus hold it more securely against accidental release.

The armature has a shank 33 thereon extending upwardly into the recess and having threaded relation with a sleeve 34, which in turn is threaded into the body of the pin and locked against turning movement by means of a feather 35. A split bushing 36 is enclosed by the sleeve 34 and grips an enlargement or head 37 on the elastic tether 30. A washer 38 is interposed between the sleeve 34 and the wall of the recess 32 and is of such size as to prevent upward movement of the split bushing 36 through the bore.

In assembling the parts, the support 14 is screwed to the bottom of the bed as described, and the magnet 20 with its pin 23 is passed through the hole in the bed, with the projecting ends of the pin aligning with the grooves 17 which guide them into position. The pin spot is then secured in place.

The magnet loses strength after prolonged usage and in order to replace it, it is simply necessary to take off the pin spot 24 and lift the magnet from its mounting in the grooves 17. Thereafter another magnet may be slipped into the support and allowed to fall by gravity to proper position. These operations are performed from above the bed of the alley and it is unnecessary for the workman to get underneath it.

The invention is not limited to the specific details of the embodiment shown and described, which may be extensively modified, and a substantial range of equivalents is contemplated within the scope of the appended claims.

What I claim as new and desire to secure by Letters Patent is:—

1. The combination with a bowling alley bed having a hole therein, of a pin spot in said hole, a magnet having its poles adjacent said pin spot, and a support loosely carrying the magnet.

2. The combination with a bowling alley bed having a hole therein, of a pin spot in said hole, a magnet having its poles adjacent said pin spot, and a support on which said magnet is movably mounted, said pin spot having means for limiting the movement of said magnet.

3. The combination with a bowling alley bed having a hole therein, of a pin spot in said hole, a magnet having its poles adjacent said pin spot, and a support having depending hangers in which said magnet is loosely mounted.

4. The combination with a bowling alley bed having a hole therein, of a pin spot removably secured in said hole, a magnet having its poles adjacent the exposed face of said pin spot, and a support having depending hangers provided with vertical grooves in which said magnet is movably mounted.

5. The combination with a bowling alley bed having a hole therein, of a pin spot in said hole having an aperture therein, a magnet extending through said aperture and having a pole disposed adjacent the exposed face of said spot, a support for said magnet having means to secure it to the bottom of said bed adjacent said hole, and means, independent of said securing means, engaging said support to maintain said pin spot and said support in assembled relation.

6. In a device of the class described, a bowling alley bed having a hole therein, a support adjacent said hole, depending hangers formed on said support having ver-

tical grooves, a magnet having trunnions movably mounted in said grooves, and a pin spot in said hole having means for limiting the movement of said magnet and provided with apertures through which the poles of said magnet extend to points adjacent the exposed face of said pin spot.

7. The combination of a bowling alley bed having a hole therein, a pin spot removably secured in said hole and provided with an aperture, a magnet having a pole disposed in said aperture, and means supporting said magnet for movement in said hole, said magnet being detachable from said supporting means and upwardly movable through said hole on the removal of said pin spot.

8. The combination of a bowling alley bed having a hole therein, a pin spot removably secured in said hole having spaced apertures, a support aligned with said hole, grooved hangers depending from said support, a U-shaped magnet, a pin extending through the legs of said magnet and having ends constituting trunnions loosely mounted in said grooves, said legs of said magnet being mounted in said spaced apertures, and a lug on said pin spot extending between the leg portions of said magnet and limiting the upward and lateral movement of said pin.

9. The combination of a bowling pin, an armature in the base thereof, an alley bed having an opening therein and a magnet in said opening movably secured to said bed whereby on the engagement of said armature with said magnet, said magnet is shiftable into close contact with said armature.

10. The combination of a bowling pin, an armature in the base thereof, an alley bed having a pair of spaced openings therein, a magnet having poles extending through said openings to the face of said bed, and a mounting for retaining said magnet on said bed but permitting it to move when engaged by said armature, whereby said poles are brought into close contact with said armature.

11. The combination of a bowling pin, an armature in the base thereof, an alley bed having an opening therein and an armature extending through said opening and pivoted for movement therein to permit movement of said magnet into close contact with said armature when said pin is deposited on said magnet.

In testimony whereof I hereunto subscribe my name.

GROVER O. WARDROP.
